UNITED STATES PATENT OFFICE.

JAMES A. CHARNLEY, OF PROVIDENCE, RHODE ISLAND.

MACHINE FOR ORNAMENTING WIRE.

SPECIFICATION forming part of Letters Patent No. 254,197, dated February 28, 1882.

Application filed December 27, 1881. (No model.)

To all whom it may concern:

Be it known that I, JAMES A. CHARNLEY, of the city and county of Providence, and State of Rhode Island, have invented a new and useful Improvement in the Art of and Machine for Ornamenting Wire; and I hereby declare that the following is a full, clear, and exact description of the same, reference being had to the accompanying drawings, forming part 10 of this specification.

This invention has reference to an improvement in the art of ornamenting wire for jewelers, and in an improvement in the machines by which the new article is produced.

15 The invention consists in ornamenting wire by rolling with rolls on which two patterns are formed spirally around the rolls, so as to form a succession of alternating patterns on the wire.

20 The invention further consists in connecting two or more rolls by driving mechanism, with their axes diverging from parallel lines, so that they approach nearer together at one end than at the other, said rolls being engraved with a 25 spiral pattern or patterns, as will be more fully set forth hereinafter.

Figure 1 is a top view of my improved machine for ornamenting wire. Fig. 2 is a vertical sectional view of the same. Fig. 3 is a view 30 of a piece of ornamental wire in which the lines or ornamentation are placed in alternately-opposite directions. Fig. 4 is a view of a piece of ornamented wire made in alternating sections. Fig. 5 is a view of a piece of ornamented wire in which the ornamentation is continuous. Fig. 6 is a view of a piece of ornamented wire in which alternately ornamented and plain globes are formed.

35 Ornamental wire for jewelers' use has heretofore been made by rolling between engraved rolls, but the action of the rolls was not continuous. Skilled labor had to be employed to attend upon the rolls and the adjustment of the same. By my improvement the wire is 40 gradually operated upon and fed automatically by the rolls. The cost of engraving the rolls is also much reduced, as only the ends of the rolls require the finished pattern engraved on the same.

45 In the drawings, A A A are three rolls supported in bearings near their ends. The cen-

tral roll has a fixed bearing, and the axis of this roll is at right angles to the frame; but the two side rolls have sliding adjustable bearings B B, and their axes are not at right angles to the frame, nor parallel to the axis of the central roll; but the axis of each of the side rolls is farther from the axis of the central roll at one end than on the opposite ends of the rolls. The surface of the rolls is therefore closer together at one end than at the opposite end. The two outer rolls are adjusted by the set-screws C C, which turn in screw-threaded bearings made in the ends of the frame, and are secured to the sliding bearings B B.

50 D D D are worm-gears secured to the driving ends of the rolls, and motion is imparted to the rolls by means of the worm E gearing into the worm-gears D D and driven by the pulley F.

55 g g are guides, between which the wire is fed and maintained at the bite of the rolls—that is to say, at the point where the rolls are closest together.

60 The wires are fed in at the end where the rolls are farthest apart, and the distance between the rolls is such as will allow the wire or rod to pass freely between the rolls at that end. The rolls gradually approach nearer to each other and impress the pattern or ornamentation deeper and deeper on the wire until the wire is surrounded by a sharply-defined 65 design or ornament, when it leaves the rolls. The pattern is engraved upon the rolls on a spiral line, in the same manner as a worm or 70 screw-thread is formed. As soon, therefore, as the wire comes in contact with the rolls it rotates with the same and is drawn through the rolls by the spiral direction of the axis of the pattern, and at each rotation the pattern is 75 pressed deeper into the wire, the wire being held in place by the guides g g and delivered in the finished condition.

80 When a continuous pattern is to be rolled on the wire the rolls are engraved with the pattern placed spirally around the rolls; but the delivery ends of the rolls only require the finished pattern, as the wire will be first operated upon by the part of the rolls nearly the thickness of the wire apart, and in rolling between the rolls is gradually drawn to the finishing end.

Various forms of alternate patterns—either in form or the shape of the wire—can be produced by my improved rolls, in which I form spiral paths around the cylinder and engrave them with different patterns. One form of the wire thus produced is shown in Fig. 4; but the configuration of the wire may also be changed in such rolls, and beaded or other ornamented wire produced.

10 *h h h* are spirals cut into the rolls. They are concaved channels, one set of which is engraved, and they form the wire shown in Fig. 6, consisting of alternately ornamented and plain balls. Both balls may be ornamented with the same or different patterns, and one ball may be made smaller than the other by changing the form of the concaved spiral channels *h h*; or one of the spiral channels *h h* may be concave and the other V-shaped, so as to produce alternate balls and cones. It will thus be seen that a great variety of ornament may be rolled on the wire by my improved machine.

15 It will be seen that two wires are operated upon in this machine at the same time, as one wire is fed on each side of the central roll.

Thus by using three rolls double the amount of work is accomplished that could be done by two rolls.

Having thus described my invention, I claim 30 as new and desire to secure by Letters Patent—

1. A machine for ornamenting wire, consisting of two or more rolls having two continuous spiral grooves formed on the same, one or both of which is engraved so as to produce 35 ornamented designs, as described.

2. A machine for ornamenting wire, consisting of a central roll supported in fixed bearings, and two rolls, one on each side of the central roll, supported in adjustable bearings, 40 on which rolls a pattern is engraved, the axis of which passes spirally around the roll, as described.

3. The combination, with the central roll A and the two side rolls A A, of the adjustable 45 bearings B B, the screws C C, and the guides g g, arranged to roll and ornament two wires simultaneously, as described.

JAMES A. CHARNLEY.
